FOLDABLE WREATH-FORMING
FOUNDATION

Roy B. Propst, Los Angeles, Calif.

Application June 3, 1949, Serial No. 96,881

3 Claims. (Cl. 41—12)

1
This invention relates to foldable wreath-forming foundations, and more particularly to wreath foundation made in sections or segments, pivotally or hingedly connected, and foldable into small compass so as to be mailed in an envelope, or small package, and which can be opened out and secured as a round foundation on which to attach greens, ferns, flowers and the like, to form a wreath.

Among the salient objects of the invention are: to provide such a foundation article that it can be used over and over again, if desired, which is durable, and sufficiently strong and rigid that it makes a firm form foundation; to provide such a foundation that it can be folded into small compass and stored in small space, or mailed to distant places; to provide such an article which is economical, practical and efficient for the purpose for which it is created.

In the accompanying sheet of drawings, I have illustrated one simple, practical embodiment of the invention referred to, and in which:

Figure 1 is a face view of said foundation, ready to receive the decoration to form a wreath;

Figure 2 is a fragmentary view showing the reverse side of one of the hinge joints and the interlock;

Figure 3 is an edge view thereof;

Figure 4 shows how the parts are folded for shipment; and

Figure 5 shows a piece of the form, provided with marginal notches to facilitate tying the decorations thereon.

Referring in detail to the drawings, in the present showing, six sections or segments are shown, pivotally connected together and interlocked. These sections or segments are designated 6, 6, each having one end round, as at 7, with a rivet hole 8, therethrough, and having its other end tapered to a point, as at 9, with a rivet hole 8', therethrough, to register with the rivet hole 8 in an adjacent round end. At the round end of each, the inner edge is provided with a notch 10, and the tapered end, adjacent this round end, is provided with a struck out kink 11, which is positioned to register with and interlock in said notch 10, as will be understood from Figs. 2 and 3.

The rivets, designated 12, are more like eyelets which can be inserted through the registering holes 8 and 8' and have their inserted ends flared or expanded sufficiently to prevent accidental removal. Any kind of rivets can be used, or any other suitable pivotal connection made.

It is only necessary to remove one of said rivets, or lift one end of one segment 6 off the rivet end,

and the several sections can be folded outwardly in the form shown in Fig. 4, thus making it easy to store, pack or mail the complete form or foundation.

5 In Fig. 5, I have indicated how each segment or section can be provided with the notches 13, 13, for use in tying greens, ferns, or other wreath materials to the form, as will be understood by those versed in the art.

10 I do not limit the invention to the details shown for explanatory purposes, except as I may be limited by the hereto appended claims.

I claim:

15 1. A foldable wreath foundation consisting of a plurality of flat metal circle segments pivotally connected at their overlapping ends to form a circular form, each section being curved, said sections being foldable together when one pivotal connection is separated, said sections, at their pivot ends, having notch and kink interlocking means for locking them into a circular form.

20 2. A foldable wreath foundation consisting of a plurality of curved flat sections, each being a segment of a complete circle, pivotally connected at their ends, one section having a notch in its edge, near its pivot and the other section having an overlapping end provided with a struck-out part near its pivot to fit said notch when said sections are opened in connected circular form, and to move out of said notch whereby said curved sections can be folded outwardly and brought together in overlapping length for packaging.

25 30 3. A foldable wreath foundation consisting of a plurality of curved flat sections, each having a round end and a tapering end to be placed together in overlapping relationship, and riveted together at said overlap, the round end of each having a notch in its edge and the tapering end having a struck-out part positioned to move into said notch as said parts are moved into operating positions to form a round foundation, said sections having notches along their edges to

35 40 45 facilitate tying wreath material thereon.
